UNITED STATES PATENT OFFICE.

BENJAMIN D. CHAMBERLIN, OF ROCHESTER, NEW YORK, ASSIGNOR TO EASTMAN KODAK COMPANY, OF ROCHESTER, NEW YORK, A CORPORATION OF NEW YORK.

NUMBERING STAMP FOR PHOTOGRAPHIC-PRINTING MACHINES.

Application filed March 5, 1925. Serial No. 13,239.

This invention relates to photography, and more particularly to photographic printing machine numbering stamps. One object of my invention is to provide a simple linkage for moving the numbering stamp in timed relation to the platen, and to and from an ink pad carried by the platen. Another object is to provide a printing machine stamp which may be readily cleaned and adjusted. Another object is to provide a stamp which may be pivoted directly to the printing machine frame and which may be operated through a single link connected to the platen moving mechanism. Another object is to provide a latch mechanism through which the stamp may be moved together with or independently of the platen, and other objects will appear hereinafter from the following specification, the novel features being pointed out in the claims at the end thereof.

This printing stamp is an improvement over the stamp shown in my copending patent application for numbering stamp for photographic printing machines, Serial No. 756,348, filed December 16, 1924, and is particularly adapted for use on the printing machine shown in my copending patent application Serial No. 756,347, photographic printing machine, filed December 16, 1924.

Coming now to the drawings, wherein like reference characters denote like parts throughout:

Fig. 1 is a side elevation showing a portion of a printing machine in section, equipped with a numbering stamp constructed in accordance with and illustrating one form of my invention;

Fig. 2 is a longitudinal section through the stamp carrier showing an elevation of the stamp;

Fig. 3 is an end elevation of the stamp and carrier; and

Fig. 4 is a plan view of the stamp and carrier removed from a printer.

I have shown my printing stamp by way of illustration as mounted upon a printing machine of the type shown in my copending application above referred to. This printer may consist of a top 1 which supports a bracket 2 at the back and a printing panel 3 in the printer top. This panel may be covered by means of a platen 4 which is pro-

vided with a rearwardly extending arms 5 pivoted at 6 to lugs 7 extending up from the printer top. The platen may be moved by means of a handle 8 which is on the end of a lever 9 which forms one arm of a bell crank lever pivoted at 10 to the platen, and having a second arm 11 pivoted at 12 to an upper link 13. Link 13 is carried by the shaft 14 which is supported by the bracket 2. Links 11 and 13 form a toggle which may exert resilient pressure upon the platen 4 through the spring support 15.

There is an aperture 16 cut in the platen through which a printing stamp 17 may operate to impress its characters upon printing paper supported by the printing panel 3. This stamp may be of any preferred type, and is here shown as consisting of a casing 18 carrying a plurality of type discs 19 which may be moved by means of an operating handle 20.

The stamp is supported in a stamp carrier 21, which is preferably channel shaped having sides 22 in one end of which 23 are apertures 24 which form a bearing for a shaft 25 which hingedly secures the stamp carrier to the table 1 through the upstanding lugs 26. At the opposite end of the sides 22 there are extensions 29, each having a pair of slots 27 through which pins 28 attached to the stamp casing 18 may slide. The stamp is normally pressed downwardly by means of a spring 30 which is attached inside the channel member against the top 21 by means of a bolt 31.

The stamp may be moved about its shaft 25 by means of the following mechanism: an arm 32, as is best shown in Fig. 2, is provided with a flat surface 33, this surface being riveted at 34 to a block 35 which may be in the form of a casting having an upwardly extending hook 36. This hook passes freely through a cut-out portion 37 in the top 21 of the channel member. It may, however, be held tightly by means of a latch 38 which is pivoted upon stud 31, and which is provided with an operating handle 39. When portion 40 lies beneath the hook, as is shown in the drawings, arm 32 in effect is integral with the stamp carrier, but, when the locking disc 38 is turned in the direction of the arrow, Fig. 4, portion 41 of the disc 105 comes opposite the hook, thus permitting the

arm 32 to separate from the stamp carrier so that the integral relation is broken.

Arm 32 is pivoted on a stud 42 which is carried by an arm 43 which is pivoted at 44 to the toggle 13. This connection causes the stamp carrier and platen to be moved simultaneously when the handle 8 is moved. In the full line positions in Fig. 1, the parts are in their operative position, in which the printing paper is being held against the printing panel by the platen. In this position, the stamp has been moved through the opening 16 in the platen, and the type discs 19 may rest against the printing paper. The dashed line positions in this figure, indicate the inoperative position of the parts in which the stamp discs 19 rest against an inking pad 49 which is carried upon a bracket 50 attached by a screw 51 to the platen 4. As the handle 8 is moved, the stamp carrier and the platen swing about their offset pivots 6 and 25, so that the stamp is inked at one extremity of the movement, and the stamp will rest against the printing paper at the other extremity of movement.

The operation of my device is as follows: the handle 39 may be moved in the direction shown by the arrow in Fig. 4, to release the latch so that the carrier may be swung up as far as necessary, as indicated in broken lines, Fig. 2, so as to clean or adjust the stamp discs 19. The carrier may be then swung back and engaged with the link 32 through the latch 38. By raising the handle 8 to move the platen 4 from the printing panel 3, link 43 through toggle member 13 causes the stamp carrier to swing about its pivot 25 into contact with the inking pad 49 carried by the platen 4. The printing material may be then adjusted on the platen 3, and the handle 8 lowered, thus bringing the platen 4 against the printing material, this causes a reverse movement of the toggle members 11 and 13, and through link 43 the stamp carrier is moved towards the printing panel so that the type discs 19 will pass through aperture 16 and a spring 30 will cause the stamp 17 to exert a light pressure upon the printing panel. The width between the supporting arms 27 for the stamp is preferably a little greater than the thickness of the stamp 17, so that the four pins and slots 27 and 28 permit a slight universal movement of the stamp, although the spring 30 also exerts a downward pressure upon the center of the stamp, thus causing a firm and even impression to be made.

While I have described my printing stamp mechanism as particularly useful with a printing machine of the type above described, certain features of my invention are applicable to different types of machines, and I contemplate as within the scope of my invention all such modifications as may come within the scope of the appended claims.

Having thus described my invention, what I claim as new and desire to secure by Letters Patent is:—

1. In a photographic printing machine having printing panel and a platen movable thereover, the combination with platen moving mechanism, of a stamp carrier hingedly attached to the machine, and a link connecting the stamp carrier and the platen moving mechanism. 75

2. In a photographic printing machine having printing panel and a platen movable thereover, the combination with platen moving mechanism, of a stamp carrier hingedly attached to the machine, an arm projecting from the stamp carrier and a link connecting the arm and the platen moving mechanism whereby the stamp carrier may be moved through the platen moving mechanism. 80

3. In a photographic printing machine having printing panel and a platen movable thereover, the combination with platen moving mechanism, of a stamp carrier hingedly attached to the machine, an arm projecting from the stamp carrier and a link connecting the arm and the platen moving mechanism, a removable connection between the stamp carrier and the arm whereby the stamp carrier may be moved independently of the platen operating mechanism at will. 85 95

4. In a photographic printing machine having a printing panel and a platen movable thereover, the combination with a frame, of a stamp carrier hinged to the frame, platen operating mechanism, connections between the stamp carrier and the platen operating mechanism, and a latch between the platen operating mechanism and the stamp carrier permitting these parts to move together or separately. 100 105

5. In a photographic printing machine having a printing panel and a platen movable thereover, the combination with a frame, of a stamp carrier hinged to the frame, a hinge connecting the platen to the frame offset from the hinged stamp carrier, platen operating mechanism, and a link between the platen operating mechanism and the stamp carrier whereby the platen and stamp carrier may be simultaneously 110 115 moved.

6. In a photographic printing machine having a printing panel and an apertured platen movable thereover, the combination with an ink pad carried by the platen, of a printing stamp carried by the machine and operable through the platen aperture, operating mechanism for the platen and printing stamp adapted for moving the platen and stamp simultaneously to make the stamp operate through the aperture when moved in one direction, and to bring the stamp into contact with the inking pad when moved in the other direction. 120 123

7. In a photographic printing machine, 130

- the combination with a printer having a panel therein, of an apertured platen pivoted to the machine and adapted to be moved to and from the panel, a stamp carrier pivoted to the machine, means for moving the platen and stamp carrier whereby the stamp will operate through the aperture in the platen when the moving means is actuated.
8. In a photographic printing machine, the combination with a printer having a panel therein, of an apertured platen adapted to be moved to and from the panel, an ink pad carried on the platen, a stamp carrier pivoted to the machine, an operating mechanism for moving the stamp carrier and platen whereby these parts may swing about their pivots to a position in which the stamp engages the ink pad.
9. In a photographic printing machine, having a printing panel and a platen movable thereover, the combination with a stamp carrier comprising a channel shaped member, a block adapted to lie in the channel having an arm extending from the block, stamp operating mechanism connected to the block, a latch between the block and the channel member, said stamp operating mechanism being also adapted for moving the platen, the latch being operable to permit the stamp carrier to be moved together with or separate from the platen.

Signed at Rochester, New York, this 2nd day of March, 1925.

BENJAMIN D. CHAMBERLIN.
